US0D1069199S

(12) **United States Design Patent** (10) Patent No.: **US D1,069,199 S**
(45) Date of Patent: ** Apr. 1, 2025

(54) **WEAPON LIGHT**

(71) Applicant: **Crimson Trace Corporation**,
Columbia, MO (US)

(72) Inventors: **Tim Meissen**, Columbia, MO (US);
William A. Planck, Columbia, MO
(US); **Shane Ball**, Columbia, MO (US);
William Garland, Columbia, MO (US);
Michael Cottrell, Ashland, MO (US);
James Tayon, Moberly, MO (US)

(57) **CLAIM**

The ornamental design for a weapon light as shown and described.

DESCRIPTION

FIG. 1 is a perspective of a weapon light;
FIG. 2 is a front view of the weapon light;
FIG. 3 is a left side view of the weapon light;
FIG. 4 is a top view of the weapon light;
FIG. 5 is a rear view of the weapon light;
FIG. 6 is a right side view of the weapon light; and,
FIG. 7 is a bottom view of the weapon light.
The broken lines in the drawings depict portions of the
weapon light that form no part of the claimed design.

1 Claim, 7 Drawing Sheets
